UNITED STATES PATENT OFFICE.

FREDERICK W. BECKERT, DECEASED, LATE OF NEW HAVEN, CONNECTICUT, BY
FREDERICK W. BECKERT, JR., ADMINISTRATOR, OF NEW HAVEN, CONNECTICUT,
ASSIGNOR TO THE GREIST MANUFACTURING COMPANY, A CORPORATION
OF CONNECTICUT.

SEWING-MACHINE HEMMER.

1,334,589.

Specification of Letters Patent. Patented Mar. 23, 1920.

Application filed June 26, 1919. Serial No. 306,877.

To all whom it may concern:

Be it known that FREDERICK W. BECKERT, deceased, late a citizen of the United States, and resident of New Haven, in the county of New Haven and State of Connecticut, invented or discovered certain new and useful Improvements in Sewing-Machine Hemmers, of which the following is a specification, reference being had therein to the accompanying drawings.

This invention relates to sewing machine hemmers and has for its object to provide an adjustable hemmer which will not be expensive to manufacture and which will be convenient and efficient in use.

In the accompanying drawings Figure 1 is a plan view and Fig. 2 a bottom view of the improved hemmer. Fig. 3 is a front view and Fig. 4 a side view looking from the left of Fig. 1. Figs. 5, 6, 7 and 8 are detail views of the several parts of the hemmer, separated from each other.

Referring to the drawings, 12 denotes a presser foot adapted to be attached to the presser bar of a sewing machine and which presser foot is provided with a raised front portion 13 having a screw hole 14 and having also a side lug 15 provided with a notch 16 at its end. Attached to the said presser foot, by a set screw 17 entering the screw hole 14 in the presser foot, is a plate or part 18 having an integral hemmer scroll 19 and a folded-over lip 20 integral with which is an attaching portion 21 which is folded over said lip 20 and which is provided with a downturned lug 22 adapted to enter the notch 16 in the lug 15 of the presser foot. The opening 23 in the attaching portion 21, which overlies the raised front portion 13 of the presser foot, and through which opening 23 the screw 17 passes, is somewhat elongated so as to permit of slight lateral adjustments of the said plate or part 18 and the stationary hemmer scroll 19 carried thereby, relative to the needle position in the presser foot indicated by the opening or slot *a* in said foot. Preferably formed integral with the folded-over lip 20 is a second reversely folded lip or lug 24 which slightly overlaps the end of the lug 15 on the presser-foot.

Sustained by the plate or part 18, which is fixed to the presser foot, is a second plate

or part 25 which is slidably mounted on said plate or part 18 between the lip 20 at 55 the rear side of said plate or part 18 and a turned-over lip 26 at the front side of said plate or part 18, said plate or part 25 being turned under at its left hand end to form a looped part 27 which embraces the stationary hemmer scroll 19 and which part 27 is provided at its inner end with a finger 28 which co-operates with a partial hemmer scroll part 29 formed on a plate 30 having an arm 31 which fits in a slot or opening 32 60 in the fixed plate or part 18 and which arm is secured to the adjustable plate or part 25 by means of screws 33.

The plate or part 25 is provided with a longitudinal slot 34 through which passes 70 a set screw 35 tapped in a thickened portion 36 carried by the fixed plate or part 18, said plate or part 25 being provided at its right hand end with a turned-up lug 37 for convenience in adjusting the said plate or part, 75 relative to the fixed plate or part 18, when the said set screw 35 is loosened for the purpose of adjusting the movable hemmer scroll parts 28 and 29 to different positions relative to the fixed hemmer scroll part 19, 80 85 for making narrower or wider hems.

From the foregoing it will be understood that the improved adjustable hemmer consists of four main parts, to wit: the presser foot 12, the plate or part 18 fixedly attached 85 to said presser foot but slightly laterally adjustable thereon and carrying the hemmer scroll part 19, the plate or part 25 adjustable relative to the said plate or part 18, and the plate 30 which is secured to the said 90 plate or part 25 and which carries a portion of the adjustable hemmer scroll.

The downturned lug 22, entering the notch 16 in the lug 15 on the presser-foot serves, in connection with the set screw 17, 95 to afford two separated points of connection of the fixed hemmer part or plate 18 with the said presser foot, so that the hemmer will be effectively steadied when in use.

The plate 25 is preferably provided with 100 a graduated scale or gage 38 which is used in connection with an index finger 39 formed integral with the lip 26 at the forward edge of the plate or part 18, the said gage and index finger being convenient in 105 indicating any desired position of adjust-

ment of the adjustable hemmer scroll parts relative to the fixed hemmer scroll.

What is claimed as the invention of the said FREDERICK WILLIAM BECKERT, deceased,
5 is:—

1. A sewing machine hemmer comprising a presser foot portion adapted to be attached to the presser bar of a sewing machine and constructed with a raised forward portion, a
10 plate fixed to said raised portion of said presser foot, a hemmer scroll depending from one end of said fixed plate and which latter is provided at its opposite edges with lips, an adjustable plate mounted between said lips and carrying hemmer scroll parts beneath said first-named plate, and means for adjustably securing said last-named plate to said first-named plate.
2. A sewing machine hemmer comprising a presser foot portion adapted to be attached to the presser bar of a sewing machine and constructed with a raised forward portion having a side lug which is notched at its end, a plate fixed to said raised portion of
25 said presser foot, a hemmer scroll depending from one end of said fixed plate and which latter is provided at its opposite edges with lips, a lug supported by said fixed plate and engaging the notched part of said
30 presser foot, an adjustable plate mounted between said lips and carrying hemmer scroll parts beneath said first-named plate, and means for adjustably securing said last-named plate to said first-named plate.
3. A sewing machine hemmer comprising a presser foot portion adapted to be attached to the presser bar of a sewing machine and having a raised forward part, a plate having a depending scroll and provided at its opposite edges with lips one of which underlies said raised portion of said presser foot, but which is provided with an upper part
40 overlying said presser foot and having an elongated opening, a set screw passing through said opening and by means of which said plate may be adjustably attached to the raised portion of said presser foot, a
45

second plate fitting between said lips and carrying, beneath the first-named plate, two hammer scroll parts, and means whereby 50 said plates may be adjustably secured together.

4. A sewing machine hemmer comprising a presser foot portion adapted to be attached to the presser bar of a sewing machine and 55 having a raised forward part having a side lug which is notched at its end, a plate having a depending scroll and provided at its opposite edges with lips one of which underlies said raised portion of said presser foot, 60 but which is provided with an upper part overlying said presser foot and having elongated opening, a set screw passing through said opening and by means of which said plate may be adjustably attached to the 65 raised portion of said presser foot, a lug carried by said plate and entering the notch in said presser foot lug, a second plate fitting between said lips and carrying, beneath the first-named plate, two hammer scroll 70 parts, and means whereby said plates may be adjustably secured together.

5. A sewing machine hemmer comprising a presser foot portion adapted to be attached to the presser bar of a sewing machine and 75 constructed with a raised forward portion, a plate fixed to said raised portion of said presser foot, a scroll depending from one end of said fixed plate and which latter is provided at its opposite edges with lips, an 80 adjustable plate mounted between said lips and carrying hemmer scroll parts beneath said first-named plate, and means for adjustably securing said last-named plate to said first-named plate, said fixed plate being 85 provided with an index and said adjustable plate having a graduated scale coöoperating with said index.

In testimony whereof I affix my signature.

FREDRICK W. BECKERT, JR.,
Administrator of the estate of Frederick W. Beckert, deceased.
